UNITED STATES PATENT OFFICE.

LESTER A. SCHAEFFER, OF DAYTON, OHIO, ASSIGNOR OF TWO-THIRDS TO
WILLIAM A. HALTEMAN AND WILLIAM G. OLWIN, OF SAME PLACE.

HAND-RAKE.

SPECIFICATION forming part of Letters Patent No. 289,567, dated December 4, 1883.

Application filed June 14, 1883. (No model.)

To all whom it may concern:

Be it known that I, LESTER A. SCHAEFFER, of Dayton, in the county of Montgomery and State of Ohio, have invented certain Improvements in Hand-Rakes, of which the following is a specification.

My invention relates to lawn-rakes; and it consists in a novel manner of forming the teeth and guard or hood, as hereinafter more fully set forth.

In the accompanying drawings, Figure 1 represents a perspective view of my improved rake; Fig. 2, the end teeth; Fig. 3, the intermediate teeth, and Fig. 4 a view illustrating the manner of securing the teeth; Figs. 5, 6, and 7, views illustrating modifications.

The object of this invention is to produce a cheap and efficient hand-rake, which shall be strong and durable in construction; and with this end in view I form said rake with a head or stock, A, and a series of teeth, B, of the peculiar construction shown. Each tooth is formed with a rounded or curved end and with two sides or branches, a and b, the former having its end bent and inserted into the stock, or, if preferred, passed entirely through the same, and the latter being passed through the stock or head and carried backward in the form of an extension, c, which extensions collectively form a hood or guard, C, to prevent the grass, leaves, &c., from falling over the head or stock. The outer or end teeth have their extensions d made much longer than the others, and curved or bent around toward and attached to the socket D, which is located midway between the ends of the stock or head, as shown. The extensions d of the end teeth thus form an outer support or frame for the hood C, to which the extensions c of the intermediate teeth are attached, as shown, said parts serving to mutually stiffen and support each other, and forming a guard or hood, through or over which leaves, grass, &c., cannot readily pass. The teeth at each side of the socket have their ends a bent inward toward the socket, so that the two sets of teeth present the appearance indicated in Figs. 2 and 3. This, however, is not essential, though preferred.

If the rake is designed for rough usage, it

will be found advisable to carry the ends a entirely through the head or stock, and to bend or clinch them, or to make a slight bend or shoulder in the extensions c d, immediately in rear of the stock, or both. The extensions c 55 are bent or coiled around the extensions d, which latter may be slightly bent or indented to prevent the extensions c from slipping or being displaced laterally. The ends of the extensions d may be passed through the socket-iron D and clinched or bent down, or secured in any other convenient manner. The flat faces of the teeth are designed to stand parallel with the length of the head or stock. A suitable handle is secured in the socket-piece 60 65 D, as usual.

Although the construction above described and illustrated in Figs. 1, 2, 3, and 4 is preferred, it will be seen that the same result, substantially, can be produced by passing both 70 branches of each tooth upward above the rake-head, where they may be twisted or locked together, as in Figs. 5 and 6, or secured to frame-wires d, in the same manner as the single branches in Fig. 1; or the guard frame-wires, 75 or both the frame-wires and the upright wires, may be made separate from the teeth, as in Fig. 7, which shows two slightly-varying arrangements. These I consider as the equivalents of the first-described construction, so far 80 as they go, and falling within my invention, but not the full equivalents.

I am aware it was proposed long ago to continue or extend the wires of which the rake-teeth were formed upward from the rake-head 85 to the handle to form braces, as is shown by the patent to Andrew J. Blodgett, dated September 1, 1857, and this I do not claim; but such braces are not adapted to answer the purpose of a hood or guard, such as is formed by 90 the extension of the teeth in my rake. The spaces between the braces will necessarily be so great as to permit grass and leaves to pass through, and the outer ends of the rake-head will not in any way be protected by the braces. 95 The hood is essentially different from the braces, which latter are still used in addition thereto.

Having thus described my invention, what I claim is—

1. The herein-described rake, consisting of head A, teeth B, and hood C, all constructed substantially as shown and described.
2. In a rake, the combination of a head, end teeth having extensions carried back of the head and inward toward the mid-length thereof, and intermediate teeth secured to the head, and having rearward extensions attached to the extensions of the end teeth, substantially as shown and described.
3. In a rake, the combination of end teeth having extensions d, meeting at the mid-length of the rake-head, and intermediate teeth provided with rearward extensions c, running directly back and attached to the extensions d, substantially as shown and described.
4. The herein-described rake, consisting of head A, teeth B, provided with extensions c
5. In a rake, a series of separate and independent teeth having their ends extended above the rake-head, and jointed together or connected, substantially as shown and described, to form a hood from end to end of the rake-head.
6. In a rake, a guard consisting of an outer frame-wire and a series of short wires extending from the frame-wire to the rake-head, substantially as shown and described.

LESTER A. SCHAEFFER.
